UNITED STATES PATENT OFFICE

FRANK M. BOUCHARD, OF ST. ELMO, ALABAMA

OIL STICK WIPER

Application filed March 23, 1931. Serial No. 524,746.

This invention relates to certain new and useful improvements in oil stick cleaner or wiper of that general class in which means are provided for cleaning the oil stick, or oil gauge rods, for wiping the oil off of the stick or rod after the same has been used for testing the height of the oil.

The present invention has for its objects, among others, to provide an improved device of this general character, which is applicable to sticks of any cross section, whether round, square or other shape, and which is capable of manufacture at small cost, durable and efficient, not liable to become broken in use, and one that does not have to be removed unless preferred, easy to install, and which will remain in position when once applied. It will be firmly held in position on the breather pipe, or filler tube, where oil is poured in the motor and at the same time entirely out of the way.

The device is simple in construction, durable, and all fear of soiling the hands is obviated.

Other objects and advantages of the invention will hereinafter appear and the novel features thereof will be specifically defined by the appended claims.

The invention, in its preferred form, is clearly illustrated in the accompanying drawing, which, with the numerals of reference marked thereon, form a part of this specification, and in which

Figure 1 is a perspective view showing the cleaner in position ready for use.

Figure 2 is a perspective view of the device ready for application to the ullage or gauge rod, or breather pipe, or filler tube.

Like numerals of reference indicate like parts in the different views.

Referring to the drawing:

1 designates a breather pipe, filler tube, or other pipe upon which it may be found desirable to affix the wiper.

2 is a container, of whatever nature, with which the pipe 1 communicates, and to this pipe 1 my cleaner or wiper is designed to be applied to wipe the oil or grease from an ullage rod used in conjunction with the container 2.

My wiper comprises a spring clasp 3 of such shape and form as to readily and firmly grasp a member 1, the shape of the latter being immaterial, in the present instance the member 3 being shown as composed of wire bent to form the portion 4 to embrace the tube 1 and then the ends are bent to form the member 5, the one end being coiled about the other, and then the one end extended to form a shank 6 terminating in an angled portion 7 as seen best in Figure 2. This angled portion is adapted to support the wipers 8, of felt, or analogous suitable material, the same being, preferably, though not necessarily, formed of one piece bent upon itself as seen at 9 to form a loop which encircles the portion 7 of the spring clasp 3, as seen clearly in Figure 2.

14 is a rod for the purpose of measuring or gauging the depth of oil in the container.

10 is a spring bent between its ends to form the cylindrical portion 11 which encircles the loop 9, as seen in Figure 2, and this spring has its free ends extended beyond the said loop to form spring arms 12-12, as seen clearly in Figure 2. These spring arms have their free ends extended outward toward the free ends of the wipers 8 as seen best in Figure 2, and upon the free ends of the said spring is placed the loop member 13, which tends to draw the wipers 8 toward each other as the said member is moved outward to compress the wipers 8 upon the rod as will be readily understood from Figures 1 and 2. The wipers 8 may or may not be secured to the arms 12; the two operate together. The arms and the wipers are normally widely divergent as seen in Figure 1.

In use, the device is applied to the breather pipe 1, as shown and the oil rod 14, and the arms 12 forced toward each other by sliding the member 13 along the arms 12, which causes the wipers to approach each other, see Figure 1, is placed between the wipers 8. The wipers may, additionally or alternatively be forced toward each other by the hand as indicated in Figure 1 so as to press upon the rod 14 and then while yet pressing firmly upon the wipers 8, the rod is drawn

through the wipers and will be quickly and easily cleaned, all the oil thereon being taken up by the wipers and this without any danger of soiling the hands of the party using the same.

The device as herein shown and described has proven most efficient in use, is capable of manufacture at very small cost, it saves the necessity of rubbing the rod in a manner which is apt to leave the hands soiled, and also avoids repeated rubbing with a rag or other wiper which always results in soiled hands.

Modifications in detail may be resorted to without departing from the spirit of the invention, or sacrificing any of its advantages, except as set forth in the annexed claims.

What is claimed as new is:—

- 20 1. An ullage rod cleaner comprising a clamp to engage a fixed support, a spring member comprising normally divergent arms supported by said clamp, wipers supported by said arms in divergent relationship to each other, whereby, upon the hand of the operator pressing the wipers toward each other upon an ullage rod and withdrawing the ullage rod from between the wipers, the rod may be cleaned.
- 25 2. An ullage rod cleaner comprising a clamp to engage a fixed support, a spring member comprising normally divergent arms supported by said clamp, wipers supported by said arms in divergent relationship to each other, whereby, upon the hand of the operator pressing the wipers toward each other upon an ullage rod and withdrawing the ullage rod from between the wipers, the rod may be cleaned, and a member embracing the arms adapted to be slid therealong to press the arms together upon an ullage rod placed therebetween.
- 30 3. An ullage rod cleaner comprising a resilient grasping member, terminating in a shank with an angled portion, a resilient member encircling said angled portion and having divergent portions, a loop member embracing said resilient member, and wipers having free ends to be grasped to press the same against the ullage rod as the same is withdrawn from therebetween.

In testimony whereof I affix my signature.

FRANK M. BOUCHARD.
